UNITED STATES PATENT OFFICE.

THOMAS B. KIRBY, OF CHICAGO, ILLINOIS, ASSIGNOR OF ONE-HALF TO
GEORGE B. ROBBINS, OF SAME PLACE.

DESIGN FOR A DRAFT-ARM FOR RAILROAD-CARS.

SPECIFICATION forming part of Design No. 24,911, dated November 19, 1895.

Application filed January 22, 1895. Serial No. 535,825. Term of patent 14 years.

To all whom it may concern:

Be it known that I, THOMAS B. KIRBY, a citizen of the United States, residing at Chicago, Cook county, Illinois, have invented and produced a new and original Design for Draft-Arms for Railroad-Cars, reference being had to the accompanying drawings, forming a part hereof.

In the accompanying drawings, Figure 1 is a perspective view of my draft-arm, looking at it from the interior and lower portion; and Fig. 2 a perspective view, looking at it from the interior and upper portion.

The leading feature of my design consists in substantially a rectangular body portion, provided with a right-angular recess on one side and near one end, a longitudinal slot extending from side to side, and a recess on both the upper and lower sides.

A is the body portion, substantially rect-

angular in cross-section, and which is provided with a slot *a*, extending longitudinally from side to side, with a recess *B* on its upper portion and a notch *b* on its lower portion. The inside front portion of the draft-arm is provided with a semicylindrical projection *C*, while the rear end of the body portion is inclosed at one end, side, and bottom to form a recess *D*, the whole presenting to the eye a harmonious and ornate figure, substantially the same as that illustrated in the drawings.

I claim—

The design for a draft arm for railroad cars herein shown and described.

THOMAS B. KIRBY.
